SEWING MACHINE DRIVE

Harold J. Le Vesconte, Western Springs, and
 Albert M. Schweda, Chicago, Ill., assignors to
 Union Special Machine Company, Chicago, Ill.,
 a corporation of Illinois

Application June 30, 1942, Serial No. 449,196

17 Claims. (Cl. 192—18)

This invention relates to sewing machines and more particularly to the driving means therefor. It has to do with a motor and clutch unit, commonly designated an electric transmitter, by which power is developed and delivered, under appropriate control, to the working parts of a sewing machine.

An object of the invention has been to provide a motor and clutch unit, for a machine of the character set forth, which is simple and compact, inexpensive to make, easy to assemble and repair, economical to operate, and readily capable of adjustment and control.

An important feature of the invention is the provision of very simple and inexpensive means for operating a clutch which controls the connection of a driving motor with the driven machine. This means comprises an axially shiftable driven clutch member connected as a unit with a driving pulley and adapted to be shifted into engagement with a driving clutch member upon the simple rocking of an arm. The clutch shifting means is associated directly with said arm and is of quite inexpensive and yet thoroughly reliable construction, involving but a few simple parts.

A further feature of the invention is the provision of an improved form of brake for arresting the rotation of the driven parts whenever the clutch is disengaged. The driven clutch member is arranged to engage a fixed brake member of substantial area quickly upon the disengagement of said clutch member from the driving member. In order to insure prompt and reliable action of the brake, the fixed braking element is made readily and finely adjustable so that it may be accurately positioned. The devices for controlling the adjustment of the brake element are readily accessible from the front of the machine. By proper manipulation of these devices, the brake may be applied as soon as the clutch is fully disengaged and care may readily be exercised to avoid any overlapping action of the clutch and brake. It is also simple to compensate for wear of the braking surfaces.

Still another feature of the invention is the particular mounting of the motor and clutch unit on a bracket or support member adapted to be secured to the under side of a work table. The arrangement is such that the unit may be readily and quickly adjusted relative to the bracket to position the driving pulley properly in relation to the driven pulley of the sewing machine and in relation to the usual belt slot through the work table. Simple and readily accessible means are

also provided for altering the relative positions of the bracket and unit in a direction to tighten or loosen the belt. This means is such, moreover, as not to interfere with the operation of the clutch and the above-mentioned lateral adjustment of the unit in relation to the bracket.

A still further feature is the provision of fan blades or air impelling vanes or ribs at a number of points in the unit so as to cool effectively the various elements which are likely to become overheated.

Other objects, features and advantages of the invention will appear from the detailed description of an illustrative form of the same which will now be given in conjunction with the accompanying drawings, in which:

Fig. I is a view, partly in elevation and partly in axial section, of a motor and clutch unit and its supporting means, constructed in accordance with the invention.

Fig. II is a top plan view of a portion of the unit, the major part of the driving motor being omitted.

Fig. III is an end elevation of the unit and its supporting means, as seen from the right end of Fig. I, with the driving pulley removed.

Fig. IV is a side elevation of the portion of the unit shown in Fig. II.

Fig. V is a vertical sectional view along the line V—V of Fig. I.

Fig. VI is a vertical sectional view along the line VI—VI of Fig. IV.

Fig. VIIA is a perspective view of a portion of the frame of the unit as viewed from the front.

Fig. VIIIB is a view of the under side of the portion illustrated in Fig. VIIA.

Fig. VIII is a detail in section along the line VIII—VIII of Fig. VI.

Fig. IXA is a perspective view of a brake element employed in the unit.

Fig. IXB is a top plan view of said brake element.

Fig. IXC is a detail in perspective of a screw employed for adjusting the brake unit.

Fig. X is a top plan view of a clutch operating arm, and

Fig. XI is a face view of the pulley as viewed along the line XI—XI of Fig. I.

Referring now to the drawings, the combined motor and clutch unit of the present invention is adapted to be mounted beneath a sewing machine table which may be of any conventional type. For this purpose a support member in the form of a hanger is provided, this having a plate-

like base portion 10 adapted to be secured to the under surface of the sewing machine table by means of screws passing through holes 11 in the plate. Extending rearwardly and downwardly from the plate and integral therewith is an arm 12 which is substantially of H formation. The lower extremities of the arm are apertured to receive a pivot pin 13. Set screws 14 passing through suitable threaded holes serve to retain the pivot pin in fixed relation to the arm. Mounted for pivotal movement about the pin 13 is a pair of lugs 15 spaced slightly from the outer faces of the arm 12 and formed integrally with a frame designated generally by the number 16. A set screw 16a passing through the end of one of the lugs 15 serves to retain the frame 16 in fixed relation to the pin 13. By loosening this set screw, or the set screws 14, appropriate adjustment of the frame on or with the pin 13, and in relation to the supporting hanger, may be effected.

The frame 16 is formed with two branches 17 and 18 having radially extending portions which are connected together at their inner ends, as indicated in Fig. III, and the main portions of which extend parallel with the axis of the unit and are connected integrally with a circular member 19 forming the end bonnet of an electric motor. Integral with this end bonnet is a forwardly projecting arm 20 which extends upwardly at a small angle, as indicated in Fig. III, and is slotted to provide a forked outer end 21. Within the slot of this forked end there is received a threaded bolt or stud 22 having nuts 23 and 24 adapted to engage and clamp the upper and lower surfaces of the fork. The upper end of the bolt 22 is enlarged and formed into a collar 25 having an opening therethrough at right angles to the axis of the bolt and adapted to receive a pivot pin 26. The latter is carried by forwardly extending ears or lugs 27 integral with the plate 10. A screw 28 serves to lock the collar 25 to the pin 26 after the parts are properly assembled.

An electric motor of any suitable construction, having a main housing 29, is carried by the end bonnet 19. The motor housing includes an outer bonnet 30 which is secured to the bonnet 19 and serves to clamp the main housing 29, by means of long bolts 31. On the bonnet 30 a socket 30a is provided into which may be plugged an electrical connection adapted to supply power to the motor. The armature of the motor is carried by a shaft 32, one end of which has a bearing, not shown, in the bonnet 30 and the other end of which is journaled in a ball bearing 33 carried by the bonnet 19. Beyond the bearing 33, there is secured to the shaft 32 a combined flywheel and clutch member 34, this being connected for rotation with the shaft by means of a key 35. The outer end of the shaft 32 is preferably threaded to receive a nut 36 which retains the combined flywheel and clutch member on the shaft.

Secured to the outer face of the member 34 is a friction band 37, formed of any appropriate frictional material and having its inner face of conical form, adapted to cooperate with the outer conical face of a cooperating clutch member 38. The latter is secured to a shaft 39 axially aligned with the shaft 32 but spaced slightly from the end of the latter. Shaft 39 is mounted in ball bearings 40 and 41 mounted within a sleeve 42. This sleeve in turn is carried by bearing blocks 43 and 44. Block 43 is integral with the frame

16 at the inner ends of the radial portions of branches 17 and 18 of the frame while the block 44 is secured to block 43 by suitable screws. The under surface of block 44 is preferably grooved, as indicated in Fig. I, to provide a corrugated effect. This assists in dissipating any heat developed in the bearing. At the outer end of the shaft 39, beyond the bearing 41, there is mounted a driving pulley 46 having a splined connection with the shaft. This pulley has a V groove in its periphery adapted to receive a V belt or a round belt which, as will be understood, is connected with the driving pulley of a sewing machine of any appropriate type. The connecting belt will normally pass through a suitable slot or opening formed in the top of the supporting table. At its outer end the shaft 39 is screw-threaded to receive a nut 47 for retaining the pulley, the bearings and related parts in assembled relation. For the purpose of lubricating the bearings 40 and 41, an oil cup 48 may be provided, this being carried by the bearing block 43 and communicating at its lower end with a circumferential groove 49, around the outer surface of sleeve 42, and through a radial opening 50 with the interior of the sleeve.

Engagement and disengagement of the clutch elements 37 and 38 is accomplished by the axial shifting of the entire assembly, including the shaft 39, bearings 40 and 41, sleeve 42 and pulley 46. Axial shifting of this assembly is produced by the rocking of an arm 51 which is mounted upon the sleeve 42. Preferably, the arm has a split collar or hub portion 52 surrounding the sleeve 42 and adapted to be clamped to the end thereof by means of a clamping screw 53. If desired, however, the arm 51 could be mounted for free rotation upon the sleeve but confined for axial movement with the sleeve. In the upper surface of the collar or hub 52 there is provided a helical groove or channel 54 (Fig. X) extending transversely across the hub at an angle to its axis. With this groove cooperates a roller 55 carried at the lower end of a bolt 56 secured to an arm 57 mounted upon the frame 16 by means of screws 58. As will be seen, clockwise rotation of the arm 51 (Fig. V) will cause the collar or hub 52 to be shifted toward the left (Fig. I), due to the camming action of the helical groove 54 on the roller 55, and will thus carry the conical face of the clutch member 38 into engagement with the friction band 37 on the flywheel. Rocking of the arm 51 in this manner may be accomplished in any suitable way, as by means of connections from a treadle (not shown) to ears 59 projecting from a face of the arm 51. This rocking of the arm is opposed by a spring 60 (Fig. V) which serves to restore the arm upon release of pressure upon the foot treadle or other control means. The counter-clockwise movement of the arm 51, in response to the spring 60, is arrested by a suitable brake which cooperates with the clutch member 38 when the clutch is disengaged. This brake will now be described.

On the outer, vertical face of the clutch member 38 a flat annular braking surface 61 is provided, this being adapted to cooperate with a friction surface 62 carried by an arcuate support 63. This support may suitably be an integral part of a block 64 whose upper end is of parallelogram configuration and adapted to slide in a groove or channel 65 cut, or otherwise formed, diagonally across the under face of the branch 18 of frame 16. A screw 66, the shank of which passes through an elongated slot 67 in the branch 18,

parallel with the groove or channel 65, is engaged with a screw-threaded opening 68 in the top of block 64 and serves to clamp the latter in any desired position. To enable accurate and fine adjustment of the block 64, thus carrying the brake surface 62 as close as possible to the surface 61 of clutch member 38 without, however, running the risk of having the member 38 simultaneously in light engagement with both the clutch band 37 and brake element 62, an adjusting screw is provided. This has screw-threaded engagement with an opening 70 in the end of block 64. An enlarged flange or disc 71, integral with or otherwise secured to the screw 69, cooperates with a depression 72 in the surface of the groove 65 to hold the screw 69 against axial movement. Turning of the screw 69 will, therefore, cause a corresponding adjustment of the block 64 along the groove 65. When properly adjusted, the block may be secured in place by the screw 66.

The operation of the unit is believed to be clear from the foregoing. When a sewing machine arranged to be driven by the unit is in use, the motor will be in constant operation through appropriate connection with a source of current. Whenever the sewing machine is to be driven, the arm 51 is rocked against the action of spring 60 and thus causes axial movement of the clutch member 38 into engagement with the revolving friction band 37 carried by the flywheel. When the end of a seam is reached, the treadle will be released and spring 60 will be permitted to lift the arm 51. This restores the clutch member 38 toward the right (Fig. I) and engages its braking surface 61 with the braking element 62. Due to the fine and accurate adjustment of the brake, only a small movement of the clutch member 38 is required and hence a very prompt application of the brake is effected upon disengagement of the clutch. Compensation for wear of the brake surface and of the clutch surface is also permitted by the adjustment of the brake supporting block 64. Such adjustment may be readily effected since the clamping screw 66 and the adjusting screw 69 are accessible from the front of the machine. However, the construction is such that a relatively large brake element may be employed so that the take-up for wear need not be effected very frequently.

Provision is made for the adjustment of the entire motor and clutch unit in relation to the supporting table. This is desirable to insure proper alignment, at all times, of the driving pulley 46 with the pulley of the sewing machine. The adjustment may be effected by simply loosening either the set screws 14 or the set screw 15a and sliding the frame 16 either with the pin 13 or relative to the latter. At the same time the pin 26 will slide in the supporting ears 27. Variation in the tension of the driving belt may be effected by appropriate adjustment of the nuts 23 and 24 along the bolt 22. So also, in the replacement of a belt, the nuts 23 and 24 may be manipulated and, if desired, the bolt 22 may be disengaged from the bifurcated extension 21.

In order to keep the unit as cool as possible in operation, vanes or ribs 73 and 74 are provided on the opposite faces of the flywheel 34. The vanes 73 induce a circulation of air over the motor housing while the vanes 74 draw air through the clutch member 38 and discharge it outwardly across the friction faces of band 37 and member 38 whenever the clutch is disengaged. When the clutch is engaged, the air impelled by the vanes 74 may pass through the flywheel at the

openings 75. So also, ribs or vanes 76 are provided in the face of the pulley 46, which is directed toward the clutch. These vanes impel the air over the bearings for the shaft 39 and particularly across the ribs or corrugations 45.

While an illustrative form of the invention has been described in considerable detail, it will be understood that numerous changes may be made without departing from the general principles and scope of the invention. The terms and expressions used herein have been employed as terms of description and not of limitation.

What we claim is:

1. In a device of the class described, a frame, a motor mounted on said frame, a clutch carried by said frame, said clutch having a member driven directly by said motor and a second member shiftable axially into and out of engagement with said first mentioned member, a brake engaged by said second member when the latter is disengaged from said first mentioned member, an arm rockably mounted on said frame, means on said frame cooperating directly with said arm to impart an axial bodily movement thereto as it is rocked, and connections between said arm and said second member for shifting the latter axially with said arm.
2. In a device of the class described, a frame, a motor mounted on said frame, a clutch carried by said frame, said clutch having a member driven directly by said motor and a second member shiftable axially into and out of engagement with said first mentioned member, a brake engaged by said second member when the latter is disengaged from said first mentioned member, a shaft connected with said second member, a sleeve in which said shaft is journaled, said sleeve being rockable and axially shiftable on said frame, an arm secured to said sleeve, said arm being operable at will by the operator, means on said frame cooperating directly with said arm to impart an axial bodily movement thereto in response to rocking thereof, and means between said shaft and sleeve for imparting the axial movements of said sleeve to said shaft.
3. In a device of the class described, a frame, a motor mounted on said frame, a clutch carried by said frame, said clutch having a member driven directly by said motor and a second member shiftable axially into and out of engagement with said first mentioned member, a brake engaged by said second member when the latter is disengaged from said first mentioned member, a shaft connected with said second member, bearing means for said shaft shiftable axially with said shaft, a rock arm connected with said bearing means, and means engaging said arm and shifting the same axially with said bearing means as the arm is rocked.
4. In a device of the class described, a frame, a motor mounted on said frame, said motor having a shaft carrying a driving clutch member at its end, a shaft aligned with said motor shaft, a driven clutch member secured to said aligned shaft, a brake normally engaged by said driven clutch member, an arm rockable about the axis of said shaft, cam means coacting between said arm and said frame for shifting said arm axially as it is rocked, and connections between said arm and said aligned shaft for shifting the latter axially with the arm to engage and disengage said clutch members and coincidentally disengage and engage said brake.
5. In a device of the class described, a frame, a motor mounted on said frame, said motor hav-

ing a shaft carrying a driving clutch member at its end, a shaft aligned with said motor shaft, a driven clutch member secured to said aligned shaft, a brake normally engaged by said driven clutch member, an arm rockable about the axis of said shaft, said arm having a collar portion surrounding said shaft, a cam groove in said collar portion, means on said frame cooperating with said groove to shift the arm axially as it is rocked, and connections between said arm and said aligned shaft for shifting the latter axially with the arm to engage and disengage said clutch members and coincidentally disengage and engage said brake.

6. In a device of the class described, a frame, a motor mounted on said frame, said motor having a shaft which carries a flywheel, a conical friction face on said flywheel, a clutch member having a radially extending body portion with openings therethrough and having a conical face at its periphery arranged to cooperate with said friction face, means for shifting said clutch member axially to engage and disengage said conical faces, brake means cooperating with a braking surface on said clutch member when said conical faces are disengaged, and air impelling vanes on said flywheel for drawing air through said openings and directing said air radially outwardly over said conical faces to cool the same and said braking surface.

7. In a device of the class described, a frame, a motor mounted on said frame, said motor having a shaft carrying a driving clutch member, a driven clutch member shiftable axially into and out of engagement with said driving clutch member, a brake element arranged to engage said driven clutch member when it is disengaged from the driving member, and means for supporting said brake element in fixed but adjustable relation to said frame comprising a block shiftable in a groove in said frame inclined to the axis of said clutch members.

8. In a device of the class described, a frame, a motor mounted on said frame, said motor having a shaft carrying a driving clutch member, a driven clutch member shiftable axially into and out of engagement with said driving clutch member, a brake element arranged to engage said driven clutch member when it is disengaged from the driving member, means for supporting said brake element comprising a block shiftable in a groove in said frame inclined to the axis of said clutch members, and screw means for shifting said block in said groove.

9. In a device of the class described, a frame, a motor mounted on said frame, said motor having a shaft carrying a driving clutch member, a driven clutch member shiftable axially into and out of engagement with said driving clutch member, a brake element arranged to engage said driven clutch member when it is disengaged from the driving member, means for supporting said brake element comprising a block shiftable in a groove in said frame inclined to the axis of said clutch members, screw means for shifting said block in said groove, and means for clamping the block in its adjusted position.

10. In a device of the class described, a frame, a motor mounted on said frame, said motor having a shaft carrying a driving clutch member, a driven clutch member shiftable axially into and out of engagement with said driving clutch member, a stationary brake element arranged to engage said driven clutch member when it is disengaged from the driving member, and means

for adjustably supporting said brake element comprising a block shiftable transversely of the axis of said clutch members in a direction at a small angle to the braking surface of said brake element.

11. In a device of the class described, a frame, a motor mounted on said frame, said motor having a shaft carrying a driving clutch member, a driven clutch member shiftable axially into and out of engagement with said driving clutch member, a brake element arranged to engage said driven clutch member when it is disengaged from the driving member, means for supporting said brake element comprising a block shiftable transversely of the axis of said clutch members in a direction at a small angle to the braking surface of said brake element, and screw means for shifting said block in said direction.

12. In a device of the class described, a frame, a motor mounted on said frame, said motor having a shaft carrying a driving clutch member, a driven clutch member shiftable axially into and out of engagement with said driving clutch member, said driven clutch member having a flat braking surface in a plane transverse to the axis of said clutch member, a brake element having a flat friction surface arranged to engage said braking surface when said driven clutch member is disengaged from the driving member, and means for supporting said brake element with its friction surface parallel with said braking surface comprising a block carrying said element shiftable in a channel in said frame disposed at a small angle to said braking surface.

13. In a device of the class described, a frame, a motor mounted on said frame, said motor having a shaft carrying a driving clutch member, a driven clutch member shiftable axially into and out of engagement with said driving clutch member, said driven member having a flat braking surface in a plane transverse to the axis of said clutch member, a brake element having a flat friction surface arranged to engage said braking surface when said driven clutch member is disengaged from the driving member, means for supporting said brake element with its friction surfaces parallel with said braking surfaces comprising a block carrying said element shiftable in a channel in said frame disposed at a small angle to said braking surface, and means for accurately positioning said block in said channel, said brake element having its friction surface disposed at said small angle to the main axis of the block.

14. In a device of the class described, a frame, a motor mounted on said frame, said motor having a shaft carrying a driving clutch member, a driven clutch member shiftable axially into and out of engagement with said driving clutch member, said driven clutch member having a flat braking surface in a plane transverse to the axis of said clutch member, a brake element having a flat friction surface arranged to engage said braking surface when said driven clutch member is disengaged from the driving member, a block carrying said brake element, said block having parallel surfaces inclined at a small angle to said friction surface, parallel guide surfaces on said frame cooperating with said parallel surfaces on said block, said guide surfaces being arranged at said small angle to said braking surface, and means for shifting said block along said guide surfaces.

15. In a device of the class described a frame, a motor and clutch unit carried by said frame,

said unit including a driven shaft having a pulley mounted thereon, a fixed support adapted to be secured to the under surface of a table, means for pivotally connecting said frame with said support, means for adjusting the vertical angular relation between said frame and support about said connecting means, said frame being shiftable axially of said connecting means in relation to said support, and means for securing said frame in any selected position in relation to said support.

16. In a device of the class described a frame, a motor and clutch unit carried by said frame, said unit including a driven shaft having a pulley mounted thereon, a fixed support adapted to be secured to the under surface of a table, means for connecting said frame with said support, said means enabling movement of said frame relative to the support in two dimensions, one vertically

for belt tightening purposes and the other horizontally for pulley aligning purposes, and means for securing the frame relative to the support in any selected position.

17. In a device of the class described a frame, a motor and clutch unit carried by said frame, said unit including a driven shaft having a pulley mounted thereon, means for shifting said shaft axially to engage and disengage the clutch, a fixed support adapted to be secured to the under surface of a table, means for connecting said frame with said support, said means enabling movement of said frame relative to the support in two dimensions, one for belt tightening purposes and the other for pulley aligning purposes, and means for securing the frame relative to the support in any selected position.

HAROLD J. LE VESCONTE.
ALBERT M. SCHWEDA.
